(57) **CLAIM**

The ornamental design for a circular knife, as shown and described.

DESCRIPTION

FIG. 1 is a top plan view of a circular knife;

FIG. 2 is a front elevational view thereof;

FIG. 3 is a bottom view thereof;

FIG. 4 is a right-side view thereof, the left-side view being a mirror image thereof;

FIG. 5 is a rear elevational view thereof; and,

FIG. 6 is an isometric view thereof.

The broken lines are for environmental purposes only and form no part of the claimed design.

The claimed circular knife is used to cut and/or peel food, especially fruits and vegetables; and can also remove food cores and central columns of oranges, lemons, apples, etc.
